UNITED STATES PATENT OFFICE.

SVEN JULIUS STRID, OF CHICAGO, ILLINOIS, ASSIGNOR TO FRED MATHEWS, OF CHICAGO, ILLINOIS.

DRAFT GEAR.

Application filed October 19, 1925. Serial No. 63,385.

To all whom it may concern:

Be it known that I, SVEN JULIUS STRID, a citizen of the United States of America, residing at Chicago, in the county of Cook and State of Illinois, United States of America, have invented a new and useful Improvement in a Draft Gear, of which the following is a full, clear, and exact description, such as will enable others skilled in the art to make and use the same.

My invention relates to draft gear for railway cars and has more particular reference to the construction and arrangement of the back-stop blocks and the side lugs against which the draw-bar yoke bears.

Heretofore, in the construction of railway car underframes, it has been the practice to provide a center-sill formed of a plurality of angle beams, and the transverse body-bolster, which is over the trucks, has been in many instances formed with side pieces extending transversely from the center-sill to the respective side-sills of the car and there is an intermediate center-filler casting placed between the center-sill members in alinement with the transverse body-bolster members. In numerous approved draft gear arrangements, the back-stop for the draw-bar yoke has been made either as a part of or separate from and abutting against the center-filler casting. As the body-bolster, including this center-filler casting, is under tremendous vertical stress in supporting the car super-structure as well as the load stress when the car is loaded, I find that the aforesaid arrangement of the back-stop with respect to the center-filler casting is objectionable because of the additional burden placed upon this casting due to the longitudinal or horizontal thrust occasioned by the push and pull upon the draft gear.

I have, therefore, designated a construction in which the thrust upon the back-stop is neither received nor absorbed by the center-filler casting, but this stress is passed through the body-bolster center-filler to a back-stop lug or fixture secured direct to the center-sill where the effect of the thrust on the draft gear is not felt by the body-bolster and its center-filler casting. The objects of my present invention are to provide a structure as last suggested, which is simple

in construction, novel in the arrangement of its parts, is compact, and is dependable as well as durable in operation.

I prefer to carry out my invention and to accomplish the divers objects thereof in substantially the manner hereinafter fully described and as more particularly pointed out in the claims, reference being here made to the accompanying drawings forming a part of this specification.

In the drawings:

Figure 1 is a top plan of a portion of a railway car under-frame, illustrating the application of my invention applied thereto, the lower half of the figure showing the center-sill, bolster, etc., in section.

Figure 2 is a vertical longitudinal section of the structure shown in Figure 1.

Figure 3 is a vertical transverse section taken through the king-bolt socket.

Figure 4 is a view similar to Figure 1, of a modification in which the back-stop block and the side lug are formed integrally.

Figure 5 is a longitudinal section, showing in vertical elevation the modification illustrated in Figure 4.

Figure 6 is a view similar to Figures 1 and 4, illustrating another modified construction.

The drawings illustrate in schematic form a typical or preferred embodiment of my invention and slight modifications thereof, and throughout the drawings, so far as practical, I have employed similar reference characters to designate like parts wherever they appear throughout the several views.

Referring first to Figures 1, 2 and 3, it will be seen the center-sill comprises two channel beams 10, 10, that are spaced apart longitudinally, with their flanges projecting away from each other and with their webs vertically disposed, in the usual manner of under-frame construction. The body-bolster consists of oppositely extending members or castings 11, 11, that are secured to the respective webs of the channels comprising the center-sill, and said members extend transversely out from the center-sill to the sides of the car. For the purpose of reinforcement and to provide continuous composite body-bolster there is a center-filler casting 12 interposed between and filling the

space between the center-sill channel-beams 10 and in longitudinal alinement with the opposite members 11 of the body-bolster and a tie plate 13 connects the assembled parts 5 in the usual manner. The yoke 14 is positioned longitudinally between the center-sill channels 10 forward of the center-filler casting and extends towards the end of the car, where it is connected to the draw-bar, 10 the coupler-jaws, or other appliance. As before stated, it has been the practice to abut the draw-bar yoke against a back-stop that is formed as a part of or is connected to the center-filler block of the body-bolster. 15 With my present invention I provide back-stops or side-lugs upon the other side of the center-filler casting from the draw-bar yoke and place blocks or extensions through the center-filler casting to engage with the rear 20 or inner end of the draw-bar yoke.

The center-filler casting which is of hollow construction is provided centrally with a tubular embossment 15 to receive the king-bolt 16, and in order to carry out my invention the casting is provided with horizontally-disposed shelves or supporting straps 25 17 and 18. Above these straps and alining respectively therewith are retaining straps 19 and 20. These sets of straps at the forward 30 and rear ends of the center-filler casting provide guides and supports for the blocks or extensions 21, which are arranged in pairs, one upon each side of the king-bolt. As seen in Figure 1, these blocks are 35 reduced slightly in width so as to extend past the king-bolt embossment 15 and the ends of these blocks project beyond the respective ends of the center-filler casting so that at their forward ends they abut the 40 rear or inner transverse end of the draw-bar yoke 14. The opposite ends of these blocks 21, in the form shown in Figures 1, 2, 3 and 6, abut the transverse webs 22 of the back-stops or side-lugs 23 that are secured to the 45 channelled members of the center-sill. These back-stops or side-lugs may be of any desired construction and are preferably re-inforced by gusset walls, as seen in the drawings. In order to prevent the accidental dislodgment of the blocks 21 in a longitudinal direction, stop-pins 24 are removably placed 50 in the upper portion of the blocks, so as to engage with the adjacent retaining strap 19.

55 In the modification illustrated in Figure 6, the stop-pins 24 have been dispensed with and the blocks 21 are widened intermediate their ends as at 25 and are provided with notches or recesses 26 to fit around the king-pin embossment 15.

60 From the foregoing, it will be seen the thrust from the draw-bar yokes received longitudinally by the back-stop or side-lugs from the blocks, will be transmitted direct to the center-sill channel members 10 and no

effect of the same is felt by the body-bolster beyond its center-filler casting, and damage to said bolster or center-filler casting, such as the shearing of the rivets or the twisting of the center-filler casting is avoided. It 70 will also be seen that I have provided an extremely simple expediency for carrying out my invention and it will be obvious that modifications other than those herein shown and described may be made without departing 75 from the principles involved, and I desire it understood that all such modifications and refinements are contemplated as coming fully within the scope of my invention as expressed in the appended claims. 80

What I claim is:—

1. In a structure of the kind described a center-sill, a body-bolster disposed transverse thereto including a center filler casting, a draw-bar yoke positioned upon one side of said casting, a back-stop therefor upon the opposite side of said casting and connected to said center-sill, and means extending from said back-stop to said draw-bar yoke whereby the thrust from the latter is transmitted through said stop to the center-sill independently of the center filler casting. 90

2. In a structure of the kind described, the center sill, a body-bolster extending transverse thereto including a center filler casting, a draw-bar yoke upon one side of said casting, a back-stop connected to said center-sill upon the opposite side of said casting, and a block extending from said stop through said center filler casting to said yoke whereby the thrust of the latter is transmitted to the center-sill independently of the center filler casting. 95

3. In a railway draft-gear a back-stop structure consisting of a plate secured to the center-sill of the car and having a member projecting laterally therefrom, and a device extending from said lateral member through the body-bolster towards the adjacent end of the car. 100

4. In a railway draft-gear a back-stop structure consisting of a plate secured to the center-sill of the car, and an elongated block extending centrally through and unsecured to the body-bolster for engagement with the draw-bar yoke, said plate having a stop lug adjacent the body-bolster engaged by the opposite end of said block. 115

5. A structure of the kind described comprising a center-sill, a body-bolster formed of alining side members positioned transversely of the center-sill and a center filler casting interposed between said side members, said casting and side member secured to said center-sill, a back-stop secured to the center-sill adjacent to and independent of the center filler casting, and an elongated block extending through said casting into engagement at one end with said back-stop 120

and adapted at its opposite end to be engaged by the draw-bar yoke.

6. A structure of the kind described comprising a center-sill, a body bolster secured transversely thereto, a draw-bar yoke within said sill upon one side of said bolster, and a back-stop for said yoke secured to said sill and provided with means whereby the longitudinal thrust of said yoke is transmitted to the back-stop and sill independently of said bolster.

7. A structure of the kind described comprising a center-sill and a body-bolster therefor, in combination with a draw-bar yoke and a back-stop for the latter positioned respectively upon opposite sides of said bolster, and a member extending through said bolster and unsecured thereto said member

at opposite ends engaged respectively by said yoke and said back-stop.

8. A structure of the kind described comprising a center-sill and a body-bolster therefor, in combination with a draw-bar yoke and a back-stop for the latter positioned respectively upon opposite sides of said bolster, and a block supported by a part of said bolster and extended therethrough whereby to engage at its opposite ends respectively with said yoke and back-stop and thereby transmit the thrust of the former to the latter independently of the body-bolster.

Signed at Chicago, in the county of Cook, and State of Illinois, this 16th day of September, 1925.

SVEN JULIUS STRID.
